ATTORNEY:

UNITED STATES PATENT OFFICE

2,663,366

TROUGH-TYPE OIL BURNER WITH FORCED COMBUSTION AIR SUPPLY

Herman R. Harris, Grosse Pointe Woods, Mich.

Substituted for abandoned application April 22, 1947, Serial No. 744,276. Divided and this application September 16, 1953, Serial No. 383,493

6 Claims. (Cl. 158—92)

1

This application is substituted for my abandoned application Serial No. 744,276, filed April 22, 1947.

This invention relates to oil burners for use within a furnace, the object of the invention being to provide a new and useful form and structural arrangement and relationship of parts by means of which oil is vaporized and air supplied to the vapor by means of a fan or blower.

These and other objects and features of the invention are hereinafter more fully described and claimed and an oil burner embodying my invention is shown in the accompanying drawing in which—

Fig. 1 is an elevation of the burner and the means for supplying air thereto.

Fig. 2 is a section taken on line 2—2 of Fig. 1.

Fig. 3 is a section taken on line 3—3 of Fig. 2; and

Fig. 4 is an elevation partly in section showing an alternative form of construction.

In the form of the invention shown in Fig. 1 a casing 1 is provided which is generally circular in form and a rotary fan is provided in the casing. The axis of the fan is eccentric to the axis of the casing 1 and, at the lower side, the casing is connected with a tube 3 which has a series of apertures 4 in one side thereof and another series of apertures 5 parallel to the first row and offset to positions on a vertical line extending approximately centrally between the respective apertures 4. A mixing tube 6 is parallel with the air supply tube 3 as will be understood more clearly in Fig. 2.

The edge 7 on the outer side of the tube 6 is higher than the edge 8 on the inner side which is below the lower row of apertures 5 so that air discharging from the tube 3 passes above the edge 8 and strikes the opposite wall of the tube 6.

This arrangement causes rotation of a portion of the air within the tube 6. On its lower side the tube 6 is provided with a trough-like element 9 in which there is a wicking 10. Oil is supplied to the wicking by means of the conduit 11 which has a manually controlled valve 12 therein and also a magnetically actuated valve in the casing 13.

An electric circuit is indicated at 15 and is connected with a thermostat, and the wires 15 extend from the thermostat to the casing 14 and wires 16 extend from one side of said casing into the end of the tube 6. The wires 16 have igniter terminals 17 just above the open end of trough 9 to which oil is delivered by the conduit 11 leading from the source of oil supply.

Casing 14 houses a high tension transformer 55

which interconnects wires 15 and 16 to supply a high tension current to the ignition terminals 17. The terminals 17 of the electric circuit are close to the surface of the fuel, such as oil, whereby the vapor at the surface of the liquid will be ignited by the discharge of an electric arc from the terminals 17 of Fig. 3 or terminals 17a of Fig. 4. The ignition of the oil within trough 9 is obtained by the discharge of an electric arc from the high voltage terminals 17, through the body of oil in said trough and to the metallic body of said trough which is properly grounded. There may be one or more such terminals 17 so connected. The ignition terminals 17 are so arranged that the electric high tension arc actually passes through the oil instantly vaporizing the same and producing a readily ignitable mixture of fuel vapor which combines with the air directed thereto. This method of ignition is described in U. S. Patent No. 2,162,572 dated June 13, 1939, and as such forms no part of the present invention which merely utilizes such method of ignition.

Preferably a plate 19 extends from the upper edge of the chamber 18 and rearwardly thereof to prevent oil from passing to the rear of the chamber 18 as shown in Fig. 3. Oil flows over the right hand edge of the chamber 18 and into the wicking 10 in the bottom of the trough 9. Preferably there are a series of spaced metal blocks 20 in the wicking which become heated in the operation of the burner and tend to vaporize the oil in the wicking.

The burner is supported by a plate 21 in the form shown in Fig. 4 and in said figure is shown an inverted cone shaped chamber 22 having apertures 23 in parallel rows through which air is discharged from the conduit 3 and across the upper surface of a flange 24 of the semi-circular trough 25 to which oil is supplied by means of the conduit 26.

In either of the structural forms of the invention indicated in Figs. 1 and 4 the same result is attained in that air flows across the flange 8 or 24 of the respective forms of the trough and strikes the opposite side 7 or 25 of the trough, which terminates vertically above the said flanges. This arrangement causes the air to whirl and to pick up vapor adjacent the oil surface which is ignited by the terminals 17 or 17a of the electric circuit in the respective forms of the device.

The motor 2 in each of the forms shown is connected in the current supply circuit 15 as indicated in Fig. 1 by means of wires 27 and 28 and a

thermostatically controlled switch 29 is positioned in the space to be heated whereby temperature change in said space either makes or breaks the circuit. The apparatus therefore functions to maintain a practically constant temperature in the space being heated.

Having described my invention, reference should now be had to the claims which follow for determining the scope thereof.

I claim:

1. An oil burner for use in conjunction with a furnace comprising an elongated horizontally arranged tubular element adapted to be positioned within the furnace, said tubular element having a series of horizontally spaced apertures through which air is laterally discharged, a blower joined to said element for delivering air thereinto, an elongated horizontal trough arranged in parallel horizontally spaced relation to said tubular element opposite said apertures, means for supplying oil to said trough, said trough being partially cut away along one of its longitudinal side walls whereby the side wall remote from said tubular element is higher than the side wall closer to said tubular element, said apertures being horizontally directed with some of them arranged below the level of the outer edge of said trough, whereby streams of air from said apertures discharge transversely over said adjacent side wall and some of said streams of air engage the remote side wall thereof for deflection towards the fuel in said trough and to produce a whirling and turbulent flow of air relative to said trough.

2. An oil burner for use in conjunction with a furnace comprising an elongated horizontally arranged tubular element adapted to be positioned within the furnace, said tubular element having a series of horizontally spaced apertures through which air is laterally discharged, a blower joined to said element for delivering air thereinto, an elongated horizontal trough arranged in parallel horizontally spaced relation to said tubular element opposite said apertures, means for supplying oil to said trough, said trough being partially cut away along one of its longitudinal side walls whereby the side wall remote from said tubular element is higher than the side wall closer to said tubular element, said apertures being horizontally directed with some of them arranged below the level of the outer edge of said trough, whereby streams of air from said apertures discharge transversely over said adjacent wall and some of said streams of air engage the remote side wall thereof for deflection towards the fuel in said trough and to produce a whirling and turbulent flow of air relative to said trough, a series of heat retaining metal elements positioned in said trough in spaced relation, and oil absorbent means positioned in said trough about said metal elements.

3. An oil burner for use in conjunction with a furnace comprising a tubular element adapted to be positioned within the furnace, said tubular element having in a side wall thereof a series of horizontally spaced apertures through which air is laterally discharged, a blower joined to said element for delivering air thereinto, an oil receiving annular trough surrounding said element with the inner edge of the trough adjacent said tubular element being lower than the outer edge of said trough, said apertures being horizontally directed with some of them arranged below the level of the outer edge of said trough whereby

the air from said apertures discharges transversely over the adjacent side wall of said trough and operatively engages the remote side wall thereof for deflection towards the fuel in said trough to produce a whirling and turbulent flow of air relative to said trough and the fuel therein.

4. An oil burner for use in conjunction with a furnace comprising a tubular element adapted to be positioned within the furnace, said tubular element having in a side wall thereof a series of horizontally spaced apertures through which air is laterally discharged, a blower joined to said element for delivering air thereinto, an oil receiving annular trough surrounding said element with the inner edge of the trough adjacent said tubular element being lower than the outer edge of said trough, said apertures being horizontally directed and arranged below the level of the outer edge of said trough whereby the air from said apertures discharges transversely over the adjacent side wall of said trough and operatively engages the remote side wall thereof for deflection towards the fuel in said trough to produce a whirling and turbulent flow of air relative to said trough and the fuel therein, said tubular element having a second series of horizontally spaced horizontally directed apertures arranged above said first series of apertures, said second series of apertures being arranged above said outer edge of said trough whereby streams of air pass over the trough laterally picking up burning gases therefrom and forming the main flame of combustion which is carried outwardly and laterally of said trough.

5. An oil burner comprising a horizontal trough, means for supplying oil thereinto, a tubular member spaced horizontally from said trough and having in a side wall thereof horizontally spaced apertures facing said trough, a blower 40 joined to said tubular member for causing a lateral flow of air through said apertures into and across said trough, the edge of the trough adjacent said tubular member being below the plane of the outer edge of said trough, said apertures 45 being horizontally directed with some of them arranged below the level of the outer edge of said trough whereby streams of air discharging from said tubular member are deflected by said outer edge of said trough to contact the surface of the oil in said trough, some of said apertures in said tubular member being so arranged that a plurality of streams of air will project across the outer edge of said trough carrying therewith a portion of the burning gases from within said trough thus forming a main flame of combustion laterally of said trough.

6. An oil burner as set out in claim 5, said tubular member being cone shaped, and said trough being annular and surrounding said tubular member.

HERMAN R. HARRIS.
